UNITED STATES PATENT OFFICE.

JENNIE MARX AND EMMA MAIER, OF NEW YORK, N. Y.

COMBINED CORSET-COVER AND BUST-SUPPORTER.

957,617.

Specification of Letters Patent. Patented May 10, 1910.

Application filed November 10, 1909. Serial No. 527,177.

To all whom it may concern:

Be it known that we, JENNIE MARX and EMMA MAIER, both citizens of the United States, and residents of the city of New York, borough of Manhattan, in the county and State of New York, have invented a new and Improved Combined Corset-Cover and Bust-Supporter, of which the following is a full, clear, and exact description.

The object of the invention is to provide a new and improved corset cover and bust supporter, designed to be worn over the corset to form a corset cover, and arranged to properly support the bust and enabling the wearer to adjust the parts for the purpose and without danger of displaying the adjusting devices through shirt waists of fine, thin texture. For the purpose mentioned, the body of the garment is made of a single back piece and two front pieces connected by lacings with the sides of the back piece, to allow of adjusting the garment, the joint being covered by overlapping flaps on the adjacent side edges of the back and front, the latter being adapted to be fastened together at the front by suitable fastening devices, and the back pieces having integral shoulder straps adapted to be fastened to elongated flaps formed interiorly on the front pieces.

A practical embodiment of the invention is represented in the accompanying drawings forming a part of this specification, in which similar characters of reference indicate corresponding parts in all the views.

Figure 1 is a front perspective view of the improvement as applied; Fig. 2 is a rear perspective view of the same; Fig. 3 is an enlarged face view of the garment spread out, parts being broken out; Fig. 4 is an enlarged sectional plan view of the improvement on the line 4—4 of Fig. 3; and Fig. 5 is a similar view of the same on the line 5—5 of Fig. 1.

The body A, of the garment has its lower edge A', terminating at the waist line of the corset B, over which the garment A is worn, as indicated in Fig. 1. The upper edges of the body A are cut out at the front and rear as indicated at A² and A³, and the upper side edges of the body are cut out to form eye openings A⁴ for the passage of the arms of the wearer, as will be readily understood by reference to Figs. 1 and 2.

The body A of the garment is made of a back piece C and the two front pieces D,

D', the said back and front pieces being provided with suitable stays E, extending a distance upward from the waist line A but terminating a distance below the upper edge of the body A. The side edges of the back piece C are adjustably connected with the side edges of the front pieces D and D' by the use of lacings F, as plainly indicated in Figs. 3 and 4, so as to permit of adjusting the body A to conform to the size of the wearer, to render the garment exceedingly comfortable and at the same time form a bust supporter, especially as the lacings F permit of drawing in or letting out at the lower, upper or middle portions, as the case may be. The lacings F are covered up at the outside by flaps G, secured to the adjacent side edges of the back piece C and the front pieces D and D', the flaps G being of sufficient width to overlap each other, as plainly indicated in Figs. 3 and 4, so as to cover the lacings even when the latter are let out as previously mentioned. Thus, if a shirt waist of fine, thin texture is worn, then the lacings F are not visible as the same are covered up by the flaps G. The front pieces D and D' are adapted to be connected with each other at the front by suitable fastening devices H, such as hooks and eyes (see Fig. 5.). Shoulder straps I, serve to connect the back piece C with the front pieces D, D', the said shoulder straps I forming integral parts of the back piece C, and are adapted to be fastened to extension flaps I', formed on the front pieces D and D' by the use of suitable fastening devices such as button-holes J and buttons J', as indicated in Figs. 1 and 3. By the use of the shoulder straps I the garment is properly supported from the shoulders of the wearer; and in order to prevent the garment from creeping upward, use is made of a strap K, provided at its lower end with a hook K', adapted to hook onto the lower end of the corset B at the front thereof, the said strap K having branch straps K², K³, of which the branch strap K² is permanently attached to the lower edge of the front piece D', while the other, lacings connecting the outer edge of tachable connection, by spring button and socket, with the lower end of the other front piece D.

From the foregoing, it will be seen that the garment shown and described can be readily placed in position and adjusted to properly fit the wearer, and to act as a bust

supporter and to perform the functions of a corset cover.

The garment may be ornamented with laces or other trimmings, to suit the fancy 5 of the wearer.

Having thus described our invention, we claim as new and desire to secure by Letters Patent:

A combined corset cover and bust 10 supporter, comprising a back piece and two front pieces, fastening means for connecting the inner edges of the front pieces with each other, lacings connecting the outer edge of each front piece with the back, and a flap

secured to the front and to the back adjacent to each lacing, said flaps overlapping on the lacings and concealing said lacings, whether the said lacings are loosely or tightly drawn.

In testimony whereof we have signed our 20 names to this specification in the presence of two subscribing witnesses.

JENNIE MARX.
EMMA MAIER
